UNITED STATES PATENT OFFICE

NUNZIO SCARPA, OF NEW YORK, N. Y.

SAFETY DEVICE FOR ELEVATORS

Application filed June 22, 1927. Serial No. 200,742.

This invention relates to safety devices for elevators, and more particularly to safety devices for elevators employed for carrying building materials in buildings which are in 5 the course of construction.

One of the objects of the invention is to provide a safety device adapted to prevent movement of the elevator from a floor of the building while the elevator is in use at that 10 floor and to thereby safeguard the workmen. Another object is to provide a device of the above nature which is practical and thoroughly efficient. Another object is to provide a device of the above nature which is simple 15 in construction. Other objects will be in part obvious or in part pointed out hereinafter.

The invention accordingly consists in the features of construction, combinations of elements, and arrangements of parts as will be 20 exemplified in the structure to be hereinafter described and the scope of the application of which will be indicated in the following claims.

In the accompanying drawing in which is 25 shown one of the various possible embodiments of this invention,

Figure 1 is a perspective view of a switch mechanism associated with the elevator;

Figure 2 is a sectional view showing portions 30 of the mechanism in larger detail;

Figure 3 is a detailed view of a circuit-closing or switch member, and

Figure 4 is a perspective view illustrating 35 a portion of a building in the course of construction and showing the electric circuits of the safety device.

Similar reference characters refer to similar parts throughout the several views of the drawing.

As conducive to a clearer understanding of 40 this invention, it may be here noted that, while a building is in the course of construction, a temporary elevator is employed for hauling building materials to the upper floors. The elevator is driven by a suitable mechanism controlled by an engineer on the ground. When a workman at a particular floor wishes to use the elevator, he signals the 45 engineer and the engineer sends the elevator up to that floor. There is a real danger en-

countered in the use of these elevators by reason of the fact that the engineer does not always know when the workmen are through using the elevator and he is apt to move the elevator up or down in response to a signal 55 from another floor, the workmen at the other floors having no means of knowing that the elevator is in use. It is one of the dominant aims of this invention to provide a mechanism by means of which this danger is removed and the workmen safeguarded.

Referring now to the drawings in detail, and first to Figure 1, there is shown a support in the shape of a rectangular board 1, made preferably of hard rubber, which is fastened, by means of bolts 2, 3, 4 and 5, to an upright 6 of T cross-section which serves as a guide for the elevator platform 7. The support 1 with the mechanism carried thereon is positioned adjacent to the floor level, one at each 60 floor of the building.

Rotatably mounted in two brackets 9 and 10 upon the supporting member 1 is a horizontal shaft 8 which is threaded throughout an intermediate portion. Collars 27 and 28 upon the shaft 8 hold the shaft against longitudinal movement in the brackets. The shaft 8 passes through a yoke 11 with which it is in threaded engagement. By rotating the shaft 8 by means of the crank 29, the 65 position of the yoke 11 may be adjusted lengthwise of the shaft 8 or transversely of the direction of movement of the elevator. As shown in Figure 2, the yoke 11 is provided with a pair of rearwardly projecting arms which take over a guide 14 secured to the supporting plate 1 by means of screws 15. The guide 14 permits the yoke 11 to slide in a direction lengthwise of the shaft 70 8 and holds the same against rotating movement.

Pivoted upon the yoke 11 by means of a pin 12 is an upwardly projecting arm 13 which carries at its upper end a roller 25. Mounted upon the arm 13 beneath the roller 75 is a contact member comprising preferably two flat springs 41 and 42 as more clearly shown in Figure 3. Secured to the upper portion of the supporting plate 1 by means of screws 17 and 18 is an insulating bracket 80 100

20 upon which are mounted a pair of spaced contacts 19. A spring 40 secured to the arm 13 bears against the supporting plate 1 and normally holds the arm 13 outwardly so that the contact member 41-42 is out of engagement with the contacts 19.

Secured upon the elevator platform 7 is a cam 26. The arm 13 is held in such position by the spring 40 that the roller 25 is in the path of the cam 26. When the elevator reaches substantially the floor level, which is just a little higher than the position shown in Figure 1, the cam 26 forces the arm 13 inwardly against the action of the spring 40 and the contact member 41-42 makes electrical connection between the contacts 19. When the device is not in use, the roller 25 may be moved out of the path of the cam by turning the shaft 8 by means of the crank 29. Also, the position of the roller 25 may be adjusted accurately into the path of the cam by rotating the shaft 8, thereby rendering unnecessary exactly accurate positioning of the support 1 upon the supporting member 6. The flexibility of the spring contacts 19 and of the contact members 41-42, and the outwardly tapering of the opening between the contacts 19 permits a certain latitude of adjustment.

Connected to the respective contacts 19 are a pair of wires 20 and 21. Referring now to Figure 4 of the drawings, there are illustrated two floors of a building under construction. At each of these floors is positioned one of the supports 1 having thereon the mechanism above described. The elevator 7 is shown positioned at the second floor. On the ground is the machinery 40 which is operated by the engineer to raise or lower the elevator. Considering the mechanism at the lower floor, the wire 21 which is connected to one of the contact members 19, is connected to a lead 23 which passes upwardly through the building. The wire 20, connected to the other of the contact members 19, is connected to a supply wire 24 which passes upwardly through the building and which comes directly from a source of electrical supply. The other supply wire of the circuit is the wire 32 which passes upwardly through the building alongside the wire 24. At a convenient position adjacent to the elevator shaft is positioned a box 30 in which is contained an electric light 30^a in back of a window having thereon suitable warning indicia, such as "Don't pull chain", as illustrated or other legends indicating that the elevator is in use. One side of this electric light is connected by the lead 33 with the supply wire 32. The other side of the electric light is connected by the wire 35 to the wire 23. Thus, when the elevator reaches any floor all of the warning signals, one on each floor, are illuminated.

The box 30 contains also a switch means such as a pull switch 31^a operated, for example, by the pull chain 31. One side of this switch is connected by a lead 44 with a wire 43 passing upwardly through the building. The other side of this switch is connected by a wire 36 with the supply wire 24. The wire 43 leads to one side of an electric light 37 positioned on the ground adjacent to the engineer's station. The other side of this light 37 is connected by the wire 39 to the supply wire 32. By means of the switch operated by the chain 31 a workman on any floor signals to the engineer.

By the above described arrangement, actuation of any of the switches 31^a which are connected in parallel across the signal circuit 24, 36, 44, 43, 39, 32, closes said circuit and actuates the operator's signal 37. Thereafter, upon closing of any one of the elevator controlled switches 19, which are connected in parallel and in an indicator circuit 20, 21, 23, 35, 33, 32, which indicator circuit is connected in parallel relation across the signal circuit, the indicator circuit is closed, and all of the indicating devices 30^a, which are connected in multiple relation in said circuit, are actuated.

Considering now more particularly the operation of this apparatus, let it be assumed that the elevator is at the ground floor and that a workman on the third floor wishes to use the elevator. The workman pulls the chain 31 to thereby operate the switch within the box 30 as many times as will be necessary to cause the engineer's lamp 37 to be flashed three times, the last pull on the chain closing the switch for continued illumination of the said lamp 37. The engineer sees this light and sends the elevator up. When the elevator reaches and is stopped at the floor where its use is desired, the cam 26 holds the arm 13 inwardly, completing a circuit through the lamps contained within the boxes 30. At each floor of the building the warning sign "Don't pull chain" is now illuminated and remains illuminated as long as the elevator remains at a floor. This indicates to and warns workmen on the other floors that the elevator is in use and that it is not available to them, so that they may occupy themselves in other duties until the elevator is ready for their use. However, even though a workman on another floor should not notice the warning and should attempt to signal the engineer, he is not able to do so because the engineer's signal light 37 is already lighted. When the workman is through using the elevator he again pulls the chain 31, opening the switch within the box 30, thereby extinguishing the engineer's signal light 37 and notifying him that the elevator is free. The engineer will then move the elevator to the ground or else to a position intermediate

floors so that the lights within the boxes 30 are extinguished.

From the foregoing, it will be seen that there is herein provided a device which 5 achieves the objects of this invention and accomplishes results of practical value. When the elevator is in use at any floor the workmen on the other floors are confronted with a notice to that effect, constituting a dependable 10 warning and hence a valuable safeguard.

As many possible embodiments may be made of the above invention and as many changes might be made in the embodiment above set forth, it is to be understood that 15 all matter hereinbefore set forth or shown in the accompanying drawings is to be interpreted as illustrative and not in a limiting sense.

I claim as my invention:

1. In a safety device for elevators, in combination with an elevator used in building construction work and controlled by an operator on the ground, a signal circuit, means in said circuit including switch means on each floor adjacent the elevator for informing the operator of the floor on which the elevator is desired for use, an indicating device at each floor adjacent the elevator for indicating when the elevator is in use, an 20 electric circuit for said indicating devices and connected in parallel across said signal circuit, said devices being connected in multiple relation in said indicating circuit, a switch positioned adjacent each floor level 25 and adjacent the path of the elevator at each floor, each of said switches being connected to said indicating circuit, and operative, when closed, to close said circuit, and means carried by the elevator and operable, when 30 the elevator reaches the floor in accordance with said signal, to close said switch at that floor, thereby to actuate all said indicating devices.

2. In a safety device for elevators, in combination with an elevator used in building construction work and controlled by an operator on the ground, an electrical signal adjacent the operator to inform him of the floor on which the elevator is desired for use, a 35 circuit therefor, a plurality of circuit closing means in said circuit, one disposed on each floor adjacent the elevator and operative to actuate the signal, an indicating device at each floor adjacent the elevator for indicating when the elevator is in use, an electric circuit for said indicating devices and connected in parallel across said signal circuit, a switch positioned adjacent each floor level 40 and adjacent the path of the elevator at each floor, each of said switches being connected to said indicating circuit, and operative, when closed, to close said circuit, and means carried by the elevator and operable, when 45 the elevator reaches the floor in accordance with said signal, to close said switch at that

floor, thereby to actuate all said indicating devices.

3. In a safety device for elevators, in combination with an elevator used in building construction work and controlled by an operator on the ground, an electric signal adjacent the operator to inform him of the floor on which the elevator is desired for use, a circuit therefor, a plurality of circuit closing means connected in parallel across said circuit, one arranged on each floor adjacent the elevator to actuate said signal, an indicating device at each floor adjacent the elevator for indicating that the elevator is in use, an electric circuit for said indicating devices and connected in parallel across said signal circuit, said devices being connected in multiple relation in said indicating circuit, a switch positioned adjacent each floor level 50 and adjacent the path of the elevator at each floor, each of said switches being connected to said indicating circuit, said switches being connected in parallel, and operative, when closed, to close said circuit, and means carried by the elevator and operable, when the elevator reaches the floor in accordance with said signal, to close said switch at that floor, thereby to actuate all said indicating devices.

In testimony whereof, I have signed my name to this specification this 18th day of June, 1927.

NUNZIO SCARPA.
